UNITED STATES PATENT OFFICE.

BERNAT MECHLOVITS, OF NEW YORK, N. Y.

DESIGN FOR BROOCH OR SIMILAR ARTICLE.

Application filed June 29, 1928. Serial No. 27,319. Term of patent 3½ years.

To all whom it may concern:

Be it known that I, BERNAT MECHLOVITS, a citizen of the United States, residing at New York, in the county of New York and State of New York, have invented a new, original, and ornamental Design for Brooch or Similar Article, of which the following is a specification, reference being had to the following drawing, forming part thereof.

Fig. 1 is a face view of brooch or similar article, showing my new design.

Fig. 2 is a side view of the same.

I claim:

The ornamental design for brooch or similar article, as shown.

In testimony whereof I have affixed my signature.

BERNAT MECHLOVITS.
